DOORSTOP

Charles W. Halsey, Evansville, Ind.

Application December 3, 1931. Serial No. 578,809

3 Claims. (CL 292—262)

This invention relates to door stops having parts carried by a door and its frame which, when engaged, will permit the door to be slightly opened for purposes of ventilation, or otherwise, but will prevent entry into the room whose door is guarded by the stop.

Heretofore, a common practice has been to provide a chain and keeper, respectively connected to the door frame and the door, the chain being provided with a member which may be engaged with the keeper when the door is closed and will also permit a slight opening of the door but without permitting detachment of the parts. Chain stops are only as strong as their links and it is possible for intruders to pry open a link, hence that class of stop possesses no great security.

It has also been proposed to provide door stops having rigid bars which permit slight opening of the door but these earlier devices have comprised several parts with special fastenings which detract from their strength and security and otherwise render them of little advantage over the old style chain stop to which reference has heretofore been made.

The object of the present invention is to provide a door stop of great simplicity, strength, and durability, which will comprise only three parts, namely an attaching plate, a locking bar, and a keeper, all of improved construction and co-operating in a novel manner.

Another object is the provision, in a door stop of the type employing a rigid bar, of a bar of improved construction having a bend or offset provided with a narrowed part adapting the bar to be engaged with the keeper and yet preventing disconnection of the bar and keeper when the door is opened to the slightest extent.

A still further object is the provision of a door stop embodying an attaching plate having an integral struck-up tongue, a rigid one-piece locking bar which has a loose or articulated connection with the struck-up tongue at one of its ends; at its other end being provided with a stop; and having its central part bent or offset and narrowed and thereat provided with rounded shoulders; and a keeper of improved construction which has an open loop whose opening permits passage of the narrow part of the bar for attachment or disconnection of the bar from the keeper and whose loop permits sliding of the bar without disconnection of the bar from the keeper, the stop on the bar being adapted to be arrested by the looped part of the keeper.

My door stop, being wholly of rigid metal, and

of only three pieces, can be inexpensively manufactured and sold at a low price, beside which, it will be difficult to damage or break by an intruder and, when not in use, will be relatively inconspicuous and present a pleasing appearance to the eye.

A practical embodiment of the invention is hereinafter described and is shown in the accompanying drawings, in which:

Figure 1 is a plan view, full lines showing the door closed and the bar engaged with its keeper, dotted lines representing the door open and held by the stop; and

Fig. 2 is a front elevation, full lines showing the bar after "reception" in the keeper and dropped down therein, ready to be locked when the door is opened, dotted lines respectively representing the positions of the bar when it is not in use, and when being introduced into the keeper or when being removed therefrom.

The device comprises only three parts, namely an attaching plate 1, a locking bar 2, and a keeper 3.

The attaching plate 1 has screw holes 4 through which screws may be passed to connect the plate to the frame 5 for the door 6.

The attaching plate has a struck-up tongue 7 whose tip is bent down into its slot as at 8 to prevent disconnection of the locking bar 2, said bar having an enlarged opening 9 through which loosely passes tongue 7 in a manner permitting the bar 2 to shift horizontally in relation to the tongue 7 and to swing in relation thereto so that the bar may be disposed in locking position or in unlocked arrangement and may be shifted and swung about as necessary.

The bar 2 is provided at its opposite end with a bent part or stop 10 which prevents the bar from becoming detached from the keeper 3 when the door is in unlocked, partially open, position.

An important feature of the present invention is the offset, narrow part 11 of the bar 2 which connects the two parts 2', 2'' of the bar. This offset, narrow part 11 enables the bar to be quickly and easily engaged with the keeper 3.

The keeper 3 has screw holes 12 through which screws may be passed into the door to attach the keeper thereto. The keeper is provided with a loop 13 which is of a vertical width a little greater than the width of part 2'' of the locking bar 2 and in which loop the part 2'' is adapted to slide. The loop 13 is open at 14, the open part being slightly longer than the vertical width of the narrow part 11 so that said narrow part may be passed through said open part 14 by swinging

the bar 2 laterally. However, once the narrow part 11 is passed through the open part 14, the broad part 2" of the bar 2 is prevented from lateral disconnection from the loop because of the width of said part 2" which will slide in the loop 13 if the door be opened. It will be understood that when the narrow part 11 is passed through the open part 14, the bar 2 drops down to the full line position, Fig. 2, so that, when the door 6 is opened, the broad part 2" is immediately engaged by the loop 13.

Rounded shoulders 15 on the parts 2', 2", connect the upper and lower edges of said parts to the narrow part 11, thus facilitating slippage when the bar and keeper are moved in relation to each other.

The stop 10 is adapted to abut the base of the loop 13 to limit the sliding movement of the bar and the extent to which the door may be opened.

When the stop is not in use, the locking bar 2 hangs freely from the tongue 7, as shown by dotted lines at the left of Fig. 2, but when it is desired to lock the door so that it can only be slightly opened for purposes of ventilation or otherwise, the bar is swung from its vertical position to a horizontal position and then is swung horizontally and, the door having been closed, the narrow part 11 may be passed through the open part 14 of the loop 13, as shown by the dotted lines at the right of Fig. 2, and the bar 2 will then drop down to the position illustrated by full lines. When the door is swung open, the lower rounded part 15 on part 2" "cams" the part 2" into the loop 13 so that the door may now be swung open until the stop 10 strikes the loop 13 without possibility of disengagement of bar 2 from keeper 3. The part exposed to the view of an intruder is the bar 2 but this being of stiff and strong construction, it will be difficult to break. There being no attachments on the bar 2, there is nothing to get out of order or to require adjustment or to be tampered with by an outsider.

What I claim is:

1. In a door stop, the combination with a keeper having a loop provided with an open side, of an attaching plate having a struck-up tongue, and a locking bar having an opening loosely engaged with the tongue which permits the bar to be swung upwardly and downwardly and shifted laterally, said bar being provided at its other end with a stop adapted to engage the keeper when the door is opened and having a narrowed offset part located between the ends of said bar, said narrowed part being adapted for passage through the open part of the loop and said locking bar thereupon being adapted to fall within the keeper and to slide in the loop without detachment therefrom when the door is swung.

2. In a door stop, a locking bar adapted for connection at one end to means for its attachment to the door frame and having a free part which may be engaged with a keeper on the door, characterized by a narrowed part located between its broader parts and disposed in angular relation to the bar, said narrowed, angularly disposed part adapting the bar for lateral engagement with, or disengagement from, the keeper when the door is closed.

3. In a door stop, the combination with a locking bar which has means for pivoting it for swinging up and down and laterally when in use, said bar having a narrowed part located between its ends and a cam-part connecting said narrowed part to the locking bar, of a keeper having a loop provided with an open side through which the narrowed part of the bar may pass, said locking bar, when entered in the loop of the keeper, being adapted to fall within the keeper and said cam-part serving to displace the locking bar to enable said bar to slide in the loop without detachment therefrom when the door is swung.

CHARLES W. HALSEY.
